(57) **CLAIM**

I claim the ornamental design for a jewelry setting, as shown.

DESCRIPTION

FIG. 1 is a side elevation view of a jewelry setting showing my new design;

FIG. 2 is a front elevation view thereof;

FIG. 3 is a top plan view thereof;

FIG. 4 is a bottom plan view thereof; and,

FIG. 5 is a perspective view thereof.

The subject matter not shown in the below described Figures, including interior surfaces, and the subject matter shown in dashed lines form no part of the claimed invention.
